UNITED STATES PATENT OFFICE.

CHARLES FRANCIS XAVER OTT, OF CORNWALL, CANADA.

CLOTH-NAPPING MACHINE.

SPECIFICATION forming part of Letters Patent No. 437,715, dated October 7, 1890.

Application filed March 26, 1890. Serial No. 345,442. (No model.)

To all whom it may concern:

Be it known that I, CHARLES FRANCIS XAVER OTT, residing at Cornwall, Ontario, in the Dominion of Canada, a subject of the Emperor 5 of Germany, have invented certain new and useful Improvements in Cloth-Napping Machines, whereof the following is a specification, reference being had to the accompanying drawings.

10 My invention has reference to improvements in machines for imparting a nap or roughened surface to cotton or woolen fabrics, and more particularly to that class of napping-machines where a series of napping-rollers are arranged in cylindrical form 15 between two revolving drum-heads, and relates, first, to a new means for occasioning the revolution of the napping-rollers; second, to a means for imparting at the same time a slight 20 lateral movement to these rollers; third, to a means for feeding the cloth so as to nap both sides of it in the course of one passage of the same through the machine.

In the drawings, Figure 1 is a longitudinal 25 vertical section through the center of a machine embodying my improvements. Fig. 2 is an end view of the same—right-hand end, as shown in Fig. 1. Fig. 3 is a vertical cross-section through the plane indicated by the 30 line ww of Fig. 1. Fig. 4 is an end view similar to Fig. 2, showing the arrangement which enables both sides of the cloth to be napped. Fig. 5 is a diagram showing the path to be 35 followed by the cloth in Fig. 4.

40 A A, the main frame of the machine, carries three shafts B C D, passing from one end of the machine to the other. The main shaft B is provided with the fast and loose pulleys b and carries two circular drums F F, which 45 in turn carry at their peripheries the napping-rollers M. This shaft carries also two sprocket-wheels b' and b^2 , from the former of which the shaft D is driven and from the latter the shaft C. The shaft D carries the 50 sprocket-wheel d , which is connected with wheel b' by a sprocket-chain b^{16} and derives its motion from it. The relative size of the 55 wheels d and b' is such that the shaft D revolves much more slowly than the shaft B.

50 The shaft C carries the sprocket-wheel c , which is connected with the wheel b^2 by a sprocket-chain c^{16} and derives its motion from

it. This shaft carries a rapidly-revolving cylindrical brush Q, which cleans the napping-rollers as they pass over it.

55 The napping-rollers M are of the kind used in machines of this character, and carry the cards or teasels which tear up the surface of the cloth as they pass rapidly over it. Thirteen of them are shown in the drawings, but 60 of course their number may vary. These rollers are carried upon bearing-plates L, which are mounted at intervals upon the revolving drums F. The bearing-plates are adjusted by means of the bolts l, which pass through 65 the plate and through a slot in the revolving drum parallel to its circumference, and long enough to allow two or three inches lateral play. When the bolts are set, the bearing-plates are held tightly in position by lugs 70 upon their surfaces, which fit into circular grooves in the sides of the drum to which they are bolted. The shafts of the rollers M extend through the bearings in the plates L, and carry at one or both ends the sprocket- 75 wheels m, by which they are driven. They obtain their motion as follows: The shaft D carries the series of sprocket-wheels d' d^2 d^3 , each of a different diameter. Upon the shaft B, but independent of its motion, revolves the 80 collar G, which carries the sprocket-wheel g. This latter may be connected by a chain g^{16} with either of the wheels d' , d^2 , or d^3 , and its speed of revolution accordingly varied. To facilitate this the collar G is capable of a 85 slight lateral motion, and may be fastened by the set-screw g^2 , so as to be directly over either d' , d^2 , or d^3 . The set-screw g^2 fastens the collar G to the sprocket-wheel g'. This wheel is 90 connected by a chain t with all of the wheels m, passing alternately under and over them, its course being clearly seen in Fig. 3. The rollers M are thus driven alternately in opposite 95 directions as far as their own proper motion is concerned, and the speed of this motion is rendered greater or less, according as the wheel g is geared to d' , d^2 , or d^3 . In addition to their motions of revolution the rollers M have a slight lateral motion. This is accomplished as follows: The shaft of each of the 100 rollers M projects in each direction a short distance through its bearing, and has upon its end a cap m', which carries a roller m². The sprocket-wheel d^4 upon the shaft D drives

by chain d^16 the wheel h , which is fast to the drum H , which revolves upon but independent of the collar G . The side of this drum toward the rollers M has near its rim a circular inclined plane h^2 , upon which the roller m^2 runs, and according as its thick or thin portion is presented is this roller, and with it the napping-roller M , pressed backward or forward. Its too rigid action is prevented by a 10 spring m^6 , interposed between the cap m' and the end of the shaft which it covers. In order to complete this motion the drum H has necessarily its duplicate at the other end of the machine, driven at precisely the same 15 speed, the thick portions of the inclined plane of one drum being opposite the thin portions of the other, and vice versa. This lateral movement does not affect the sprocket-wheels m , which are keyed upon the shaft of the roller 20 M so as to allow it to slide through them. Their position is maintained constant by the projecting flange h' upon the drum H . Thus far only the parts of the machine which operate the napping-rollers have been described. 25 It remains to mention those which effect the movement of the cloth to be napped.

The main frame of the machine A supports two large stationary drums E . These drums are outside of but concentric with the 30 two pairs of revolving drums F F H H , which have been described, and are of somewhat greater diameter. At intervals around their edges are bolted adjustable bearing-plates K . They are adjusted by means of bolts K^6 , which 35 pass through the plates and through slots K^5 in the drums E , parallel to their circumference and long enough to allow several inches of lateral play. When the bolt is set, the bearing-plate is held in place by lugs upon 40 its surface which fit into a circular groove in the side of the drum to which it is bolted. The number of the plates K is immaterial, five or six generally being all that are required. They are similarly placed on both sides, and 45 between the corresponding ones on each side are supported the cloth-rollers N . The bearing-plates have each more than one bearing-hole drilled through them, so that the rollers may be placed farther from or nearer to the 50 shaft B , as may be desired. The position of the bearing-holes is seen in Fig. 2.

The cloth-rollers have sprocket-wheels n upon them, which are driven by the chains d^7 from the wheels d^5 upon the shaft D , as is 55 shown in Fig. 3. The cloth-rollers are so adjusted that the cloth in passing from one to another comes within reach of the action of the napping-rollers as the drums F revolve. The cloth runs off from the roller P , and after 60 passing a pair of tension-rollers S S goes to the cloth-rollers N . After passing these it is wound up on the take-up roller R , which rests in slotted bearings upon the rollers R' R^2 , which are driven by sprocket-wheels r' r^2 , 65 actuated by a chain r^6 from the wheel d^6 upon the shaft D .

The operation of the machine is as follows:

The drums F revolve with the shaft B , carrying with them the napping-rollers M . The independent motion of the napping-rollers 70 depends upon the rapidity of the revolution of the collar G . It is evident that if this revolves at the same speed at which the shaft B revolves there will be no independent motion of the rollers at all. On the other hand, if 75 the collar G revolves more slowly or more rapidly than the shaft B the rollers M will be rotated in one direction or the other, and the rapidity of this rotation will depend upon the difference which exists between the speed of 80 the rotation of the collar G and that of the shaft B . Furthermore, if G revolves more rapidly than B those rollers under which the chain t passes will have an independent motion 85 in the same direction as that of the drums F , and those over which the chain t passes will have an independent motion in the reverse direction. On the other hand, if G revolves more slowly than B the above motions 90 will be reversed. By varying the speed of the collar G according as the wheel g is geared to the wheel d' , d^2 , or d^3 , the rapidity of the revolution of the napping-rollers can be varied 95 at will. As the drums F revolve, they bring to bear upon the surface of the cloth to be 100 napped, first a napping-roller revolving in one direction and then one revolving in the opposite direction. The napping process is much more rapidly accomplished under these conditions than where all the rollers are driven in the same direction, for a given fiber upon the surface of the cloth is pulled first in one direction and then in another, and therefore much more quickly disengaged from the body of the fabric. At the same time the rollers have, as has been before explained, a lateral motion, the rapidity of which depends upon the relative difference between the speeds of the shaft B and the drum H . This may be varied by varying the size of the wheel d^4 . 110 This lateral motion further increases the separating power of the napping-rollers. The napping power of the machine is so greatly increased by these varying motions that in the case of many fabrics it is not necessary to run 115 the cloth clear around the cylinder before one surface is properly napped, as in Fig. 3, but the path of the cloth may be arranged, as in Fig. 4, so that both surfaces are napped in the course of one passage through the machine. 120 Large rollers U are here placed in some of the bearing-plates as well as the smaller cloth-rollers N , which have been described.

The path of the cloth in Fig. 4 is as follows: Leaving the roller P it passes under N' , over N^2 , under N^3 , by which time one surface has 125 been napped. It then comes back on itself, passing over U' and under V^2 and V^3 , where its unnapped surface again meets the napping-rollers. It then passes over N^6 , around U^4 , over N^8 and N^7 , around U^3 , under N^6 and N^4 , by which time its other surface is napped. 130 It then passes around U^2 , under N^5 , and around V' to R , where it is taken up. Part of this

course may be more clearly traced in Fig. 5. It will be seen that one side of the fabric is napped during that part of the course of the cloth when it moves in the same direction with the revolving drums F, while the other side is napped while it is moving against the motion of the drums. The latter side will therefore receive more napping. This is desirable, for it is customary to have the right side of the fabric more thoroughly napped than the other.

It will be noticed that in Fig. 5 the sprocket-chain *t* is shown as passing around the outside of all the rollers *m* instead of passing alternately over and under them. This of course causes all the rollers to revolve in the same direction, and is an arrangement which may be used in place of the alternative arrangement shown in Fig. 3 without otherwise altering the operation of the machine.

Thus far the gearing by which the collar G is put in motion, and through it the napping-rollers, has been spoken of as situated at one end of the machine only. To insure perfect uniformity of motion this gearing and the collar should be duplicated, as in Fig. 1. Each of these acts only upon every other roller, and as one is going faster and the other slower than the drums revolve the rollers are driven alternately in different directions.

Having thus described my invention, I claim—

1. In a napping-machine, the combination of the main shaft B, the drums F on said shaft, napping-rollers M, carried between the drums at intervals around their periphery, the wheels *m* at the extremities of the napping-rollers, the collar G, around the main shaft but independent of its motion, means for driving said collar at any rate of speed, the chain *t*, driven by said collar and passing alternately over and under the wheels *m* and driving them alternately in opposite directions, substantially as set forth.

2. In a napping-machine, the combination of the main shaft B, the drums F on said shaft, napping-rollers M, carried between said drums at intervals around their periphery and having their shafts extending through their bearings, means for producing axial rotation of the rollers, other drums H, outside the drums F, revolving upon the same center but inde-

pendent of the shaft B, and the inclined planes *h*², running around the inner side of the peripheries of said drums H and acting upon the extended ends of the shafts of the napping-rollers M, so as to cause the lateral play of the same, substantially as set forth. 55

3. In a napping-machine, the combination of the main shaft B, the drums F on said shaft, napping-rollers M, carried between said drums at intervals around their peripheries, means for imparting axial rotation to these rollers, the stationary drums E, larger than and outside the drums F, the cloth-rollers N, arranged at intervals between the peripheries of the drums E, the rollers U' V² V³, placed outside the rollers N, by which the fabric to be napped, after passing around part of the circle upon which the napping-rollers act with one surface presented to their action, may be carried around to the other side of said circle and the other side of the fabric presented to the action of the remaining portion of the circle, substantially as set forth. 60 70 75

4. In a napping-machine, the combination of the main shaft B, the drums F on said shaft, napping-rollers M, carried between bearing-plates arranged at intervals around the peripheries of the drums, bolts *l*, playing in circumferential slots, whereby said bearing-plates may be laterally adjusted, and means for producing axial rotation of the rollers M, substantially as set forth. 80

5. In a napping-machine, the combination of the main shaft B, the drums F on said shaft, napping-rollers M, carried between said drums at intervals around their periphery, the stationary drums E, larger than and outside the drums F, cloth-rollers N, carried between bearing-plates K, arranged at intervals around the peripheries of the drums E, and bolts playing in circumferential slots in the drums E, whereby the bearing-plates K may be laterally adjusted, substantially as described. 85 90

CHARLES FRANCIS XAVER OTT.
